EVERTING DEVICE

Margaret T. Horsley, Houston, Tex., assignor of
one-half to Joseph Woerner, Houston, Tex.

Application April 29, 1950, Serial No. 159,096

15 Claims. (Cl. 223—42)

1

This invention relates to new and useful improvements in an everter device. The invention relates particularly to a device for turning or reversing elongate tubular fabric articles such as belts or the like.

As is well known, tubular fabric articles such as belts are ordinarily sewn together with their inner sides faced outwardly and the reversal or turning of such articles, particularly when the article is elongate, has presented somewhat of a problem. It has been the practice to accomplish this reversal by use of a slender rod or pencil or by attaching one end of a string to the end of the tubular article prior to its being sewed together but both of these methods are inadequate and time consuming.

It is one object of this invention to provide an improved device for efficiently and quickly turning or reversing tubular fabric articles, such as belts and the like.

It is another object of this invention to provide a device having an elongate cylindrical stem portion provided with retractable gripping members at one end with a simple manually operable actuator for controlling the gripping members at its opposite end, whereby the reversal or turning of tubular fabric articles is facilitated.

Still another object of this invention is to provide a device of the character described, wherein the handle portion may also function as the usual darning ball or egg.

Still another object is to provide a device, of the character described, wherein removable tip elements of various contours may be mounted on the free end of the device and may be employed for pushing out collar points and for other similar purposes in the sewing of fabric articles.

Other and further objects of this invention will appear from the following description.

In the accompanying drawings which form a part of the instant specification and which are to be read in conjunction therewith and wherein like reference numerals are used to indicate like parts in the various views:

Figure 1 is a view partly in section and partly in elevation of a device constructed in accordance with the invention and showing the gripping members or elements in a retracted position.

Figure 2 is a view partly in section and partly in elevation illustrating the manner in which the device is employed in accomplishing the reversal or turning of a fabric article.

Figure 3 is a partial view illustrating the device being used for threading elastic or similar material through a tubular hem.

2

Figure 4 is a view similar to Figure 1 and showing a slightly modified form of mounting the handle on the cylindrical operating rod.

Figure 5 is a view similar to Figure 1 with the gripping members expanded and illustrating a ball of different material secured to the operating rod.

Figure 6 is a view of the ball handle being employed as a darning ball.

Figure 7 is a sectional view of a tip element arranged to be engaged over the outer end of the device, which tip element is adapted for use in pushing out collar points and the like.

Figure 8 is a view similar to Figure 7 but showing another type of tip element which may be used for pushing out rounded end members, such as glove fingers, and

Figure 9 is a view illustrating the tip element shown in Figure 8 being employed for pushing out or darning glove fingers.

In the drawings, the numeral 10 designates an elongate tubular body or sleeve having an axial bore 11 and having a smooth outer cylindrical surface. A pair of diametrically opposed arms 12 extend radially from one end of the sleeve 10 and as shown in Figure 1, the inner portion of each arm 12 is secured to the sleeve by crimping the end of said sleeve over said inner portion of each arm. An elongate cylindrical operating rod 13 extends through the bore 11 of the sleeve and has one end formed with a recess 14 which receives the inner ends of spring gripping members 15. The gripping members 15 may be formed of flexible wires and the inherent resiliency of the members tends to urge the same outwardly at all times. The lower end of each gripping member 15 is formed with an inwardly disposed gripping projection 16. The rod 13 telescopes the sleeve 10 and when in the position shown in Figure 1 the gripping members 15 are confined within the bore of the sleeve and are maintained in a retracted position.

That end of the rod 13 opposite the end to which the gripping members 15 are attached has a relatively large ball 17 secured thereto and in Figure 1 the ball is shown as constructed of wood with the end of the rod 13 threaded thereinto. A coil spring 18 surrounds the rod and is confined between the ball handle 17 and the radially projecting arms 12 and said spring constantly exerts its pressure to urge the rod in a direction which will maintain the gripping members in a retracted position. For limiting the telescoping movement of the rod with respect to the sleeve 55 in the direction in which said rod is moved by the

spring 18, the sleeve may be provided with a stop pin 19 arranged to be engaged by a collar 20 on the rod. Of course, it is apparent that any suitable stop means such as an internal shoulder within the sleeve adapted to coact with a shoulder on the rod could be employed.

In using the device, the operator grips the ball handle 17 and threads the sleeve 10 through the tubular fabric article A, as illustrated in Figure 2. The fabric article has been previously sewed with its inner surface facing outwardly and upon reaching the end of the article the sleeve 10 is telescoped on the rod 13 to depress the spring 18. This operation is facilitated since the operator can merely engage the forefinger and the middle finger with the radial arms 12 while the ball 17 is maintained in the palm of the hand. The telescoping of the sleeve with respect to the rod permits the gripping members 15 to be projected outwardly of the end of the sleeve whereby the inherent resiliency of the gripping members expands the gripping projections sufficiently to permit the material of the fabric article being turned to be engaged therebetween. Upon a release of the radial arms 12 the spring 18 will automatically telescope the sleeve with respect to the rod to retract the gripping members 15 into the bore of the sleeve, and thus the fabric is efficiently gripped between the gripping projection 16 of the gripping members. The spring maintains the gripping members engaged with the fabric because said gripping members are held within the bore of the sleeve by the pressure of said spring. The operator need then only pull the entire device by means of the handle back through the tubular fabric article A in the manner shown in Figure 2 and a reversal or turning of the article is thereby accomplished.

In Figure 3 the device is illustrated as threading elastic B or other material through a tubular hem C of a fabric article and the operation will be as above described.

The ball handle 17 not only functions as a manual grip to permit the operator to manipulate the device but this ball may also be employed as a darning ball. Such use is illustrated in Figure 6 wherein the heel of the usual sock D is illustrated as engaged over said ball. Thus, by making the ball 17 either spherical or oval shaped, it will have the dual function as a handle or grip as well as a darning device.

In the sewing of fabric articles such as dresses, there are portions of such articles which have sharp corners, such as the collar points, and it is desirable after reversing the collar that the points thereof be pushed out. The device shown herein may be employed for this purpose by placing a tip element 21 shown in Figure 7 over the end of the sleeve 10. The element 21 may be constructed of any suitable material, such as wood or plastic, and is provided with an axial recess 22 which frictionally engages the outer surface of the sleeve 10. Thus, the device may be readily used as a pushing tool.

Certain articles, such as gloves, also require turning and darning, and in order to make the device adaptable for these purposes a tip element 23 constructed as shown in Figure 8 may be employed. This tip element has a rounded outer surface and is provided with an axial recess 24 which will frictionally engage the end of the sleeve 10. The use of the tip element 23 is clearly illustrated as applied to the fingers of a glove E in Figure 9.

The ball 17 which has the dual function of a gripping handle and a darning ball may be constructed of wood, plastic or any other suitable material. As shown in Figure 1, the ball is threaded onto the rod 13 but may be attached in any desired manner. In Figure 4 a rod 13a which is similar in construction to the rod 13 is provided with a flange 25 which is fastened by screws 26 to a metallic ball 17a. In this form, the radial arms 12a are substituted for the arms 12 and have their inner ends secured to a collar 27 which is threaded onto the end of the sleeve. Also, in this form of the invention, instead of the gripping members 15 being engaged and crimped within a recess 14, said members are soldered or otherwise fastened to the end of the shaft 13a.

Still another modification in structure is illustrated in Figure 5 wherein a plastic ball 17b has an internally threaded metallic sleeve 28 molded therein and the upper end of a rod 13b threads into this sleeve. In this form, the radial arms 12b are soldered, welded or otherwise fastened to the end of the sleeve 10 instead of being secured thereto by crimping, as in Figure 1. In the form shown in Figure 5 the gripping members 15 have their ends secured within a short shaft member 29 which has connection with the end of the rod 13b by means of the threaded pin 30.

The devices shown in Figures 4 and 5 are merely modifications in structure of the device shown in Figure 1 and are used and operated in an identical manner.

From the foregoing, it will be seen that a utility device for use in sewing and darning of fabric articles is provided. The device itself is a simple and efficient tool which facilitates the turning of tubular fabric articles, such as belts, and which also facilitates threading of elastic or other material through tubular hems. The handle of the device functions as a darning ball while the tip element attachments shown in Figures 7 and 8 provide means which will permit most any type of turning or pushing operation on different fabric articles to be performed without difficulty. It is, of course, understood that the tip elements are readily removable and are thus in the form of an attachment which gives the device wide spread utility.

From the foregoing, it will be seen that this invention is one well adapted to attain all of the ends and objects of the invention hereinabove set forth, together with other advantages which are obvious and which are inherent to the structure.

It will be understood that certain features and subcombinations are of utility and may be employed without reference to other features and subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

Having described the invention, I claim:

1. A device for turning tubular fabrics including, an elongate tubular sleeve having a radial projection at one end thereof, a rod slidable within the sleeve with one end extending from that end of the sleeve on which the projection is mounted, a handle element secured to the extending end of the rod, flexible inherently expansible gripping

members carried by the opposite end of the rod and movable into and out of the bore of the sleeve in accordance with the movement of the rod relative to the sleeve, said members being expanded into a non-gripping position when located outside of the bore of the sleeve and being retracted into a gripping position when moved inwardly of the bore of said sleeve, and spring means acting upon the rod of said sleeve for constantly urging the rod in a direction which will move the gripping members inwardly of the bore of the sleeve.

2. A device for turning tubular fabrics including, an elongate tubular sleeve having a radial projection at one end thereof, a rod slidable within the sleeve with one end extending from that end of the sleeve on which the projection is mounted, a handle element secured to the extending end of the rod, flexible inherently expansible gripping members carried by the opposite end of the rod and movable into and out of the bore of the sleeve in accordance with the movement of the rod relative to the sleeve, said members being expanded into a non-gripping position when located outside of the bore of the sleeve and being retracted into a gripping position when moved inwardly of the bore of said sleeve, and a coiled spring surrounding the extending end of the rod and confined between the handle element and the end of the sleeve and exerting its pressure to constantly urge the rod in a direction relative to the sleeve which will move the gripping members inwardly of the bore of said sleeve.

3. A device as set forth in claim 2, wherein the handle element is generally spherical and is threaded onto the extending end of the rod.

4. A device as set forth in claim 2, wherein the

handle element is generally spherical and wherein the end of the rod is flanged and abuts said handle element, and screws for fastening the rod to the element.

5. An everter device including, an elongate tubular sleeve, a rod slidable within the bore of the sleeve and having one end projecting from the sleeve, gripping means carried by the opposite end and movable into gripping and non-gripping positions in accordance with the position of the rod relative to the sleeve, a handle element on the projecting end of the rod, spring means between the handle and the sleeve for urging the rod in one direction with respect to the sleeve, and projections adapted to be engaged by the fingers of the operator extending outwardly from and secured to the sleeve, said gripping means comprising flexible wire members having an inherent resiliency tending to move them to a non-gripping position, whereby when the rod is moved to dispose the members outside of the bore of the sleeve, said members are expanded into non-gripping position and when the rod is moved in an opposite direction relative to the sleeve to locate the members within the bore of the sleeve, said sleeve coacts with the members to retract them into a gripping position.
